Primary Examiner — Philip S Hyder*Assistant Examiner* — Roselynne Cody(74) *Attorney, Agent, or Firm* — Michael Best & Friedrich LLP**CLAIM**

I claim the ornamental design for a tool bit, as shown and described.

DESCRIPTION

FIG. 1 is a front perspective view of a tool bit of the invention. FIG. 2 is a right side view of the tool bit of FIG. 1, with the left side view being identical to the right side view.

FIG. 3 is a top view of the tool bit of FIG. 1, with the bottom view being identical to the top view.

FIG. 4 is a front view of the tool bit of FIG. 1; and, FIG. 5 is a rear view of the tool bit of FIG. 1. The portions of the tool bit shown in broken lines are included for the purpose of illustrating environment and form no part of the claimed design. The portions of the tool bit shown in broken lines having unequal length segments illustrate the boundary of the claimed design and form no part of the claimed design.
